RAILROAD CROSSING AND SWITCH
CONSTRUCTION

Vangel Theodos, San Francisco, Calif.

Application September 30, 1940, Serial No. 359,009

7 Claims. (Cl. 246—460)

This invention relates to railway crossings, switches and the like, and has for one of its objects improved construction providing for quick replacement of parts where there is excessive wear without disturbing the main elements that are secured to ties and without necessitating the digging away of pavement or the street surface in those cases where the rails and crossings are seated in pavements. Another object of the invention is improved means for securing means for securing wearing blocks in crossings, etc., in which the blocks are secured against any possibility of shifting or loosening, and against unequal strain and in which the means employed for securing the blocks in place are fully protected against injury from water, rust, and which means is not readily accessible to unauthorized persons for removal thereof.

Another object is an improved crossing that is more solid and less susceptible to injury than heretofore, and which can be quickly and accurately installed by relative inexperienced labor.

In the drawings,

Fig. 1 is a plan view of a complete crossing showing my invention.

Fig. 2 is an enlarged plan view of one of the crossing points of the crossing shown in Fig. 1.

Fig. 3 is a sectional view taken along line 3—3 of Fig. 2.

Fig. 4 is a sectional view taken along the 4—4 of Fig. 1.

Fig. 5 is a sectional view taken along the line 5—5 of Fig. 1.

Fig. 6 is a fragmentary sectional view taken along line 6—6 of Fig. 3, through the block just above the bolt heads.

Briefly described, the present invention relates, in general, to structure similar to that shown in my United States Letters Patent No. 1,979,583, dated November 6, 1934, and No. 2,231,232, dated February 11, 1941, in that the invention relates to structure incorporating a wearing block that is replaceable. In the above disclosures, I have employed pins to hold the blocks in place at crossing intersections or switch points, which pins are positioned to extend angularly through the upper corners of the blocks and through the side walls of the recesses in which the blocks are disposed. Thus the blocks were virtually "toenailed" in place. This structure is satisfactory in firmly securing the wearing blocks in position, but where the crossings or switches are imbedded in the pavement, it is necessary to dig away the pavement to remove the holding pins, with the result that the pavement must be repaired. Also,

in some instances the pins are accessible to being tampered with by unauthorized persons.

Heretofore various attempts have been made to use bolts, either horizontal or vertical, to secure removable blocks in place at intersections or switch points. The use of horizontal bolts again requires digging up the pavement to effect replacement, and in any event, the use of such bolts has not been effective for holding the blocks sufficiently rigid in their recesses. The use of vertical bolts, where stud bolts are used, has been proven of little value since the threads are formed in the castings supporting the blocks, and these deteriorate rapidly, thus requiring replacement of the block receiving castings, with the result that the main purpose of the invention is defeated.

In my invention, vertical bolts are used, and the block receiving castings are formed so that the bolts may be positioned for replacement from within the block receiving cavity, thus eliminating all necessity for destroying the pavement to effect replacement of the wearing blocks, and furthermore, I use bolts carrying nuts to effect securement of the blocks in place, thus eliminating threads in the blocks or block receiving castings, and making it a simple and cheap matter to replace the bolts and nuts with the blocks.

In Fig. 1 I show a crossing including the four crossing points, indicated A, B, C, D. This crossing is one in which the pairs of rails cross each other at about a 25° angle, thus forming two frogs at each of the four intersections. In two-way traffic on each pair of rails, the pairs of frogs at crossings B and C receive excessive wear, while only one of the frogs at crossings A and D receive such wear. In a switch, there is, of course, one fixed frog and a movable frog tongue, while in right angle crossings, as in the aforementioned patent, the wear occurs at the adjacent ends of the right angle rails at each crossing point that, in a way, corresponds to the frogs in Fig. 1.

In Fig. 1, there are four main castings, generally designated 1, each of which carries four arms 2 integral therewith, two of the arms on each casting substantially abutting at their ends the two ends of a pair of arms on one of the other crossings to form four equally spaced crossing points. Each of these arms corresponds, in structure, to the splice bar disclosed in my United States Patent No. 2,151,361, dated March 21, 1939, and as indicated in Figs. 4, 5 herein.

The substantially adjoining arms that extend toward each other from the castings 1 receive

rails 3 that extend the full distance between castings 1, and across the adjoining ends of the arms. The rails 3 are bolted to said arms, the latter thus constituting, in effect, fish plates that are integral with the castings. The arms that project outwardly from the crossing receive the ends of the rails that continue outwardly from said crossing, and to which arms, said ends are bolted. It is to be noted that the rails 3, and also the outwardly continuing rail sections, are secured against the opposingly facing sides of corresponding pairs of arms.

Castings 1 are each formed with a generally rectangular, upwardly opening recess that extends substantially between the adjacent ends of the arms 2 at each crossing point, and a base plate 4, preferably of rolled sheet steel, extends below each casting and under the adjacent ends of arms 2 at opposite sides of each casting. Plates 4 are welded to the castings so as to be substantially integral therewith.

The recess in each casting has side walls 5 and end walls 6 (Figs. 2, 3), which walls are of appreciably greater thickness at their lower portions that extend upwardly from the bottom 7 of the recess, then at their uppermost margins, and a horizontal shoulder 7' is thus formed around the inner sides of the recess at the junction between the lower portions and uppermost margins. The inner surfaces of said margins are substantially vertical, while the inner surfaces of the lower portions of said walls taper inwardly from said shoulders. The thickened lower portions of said walls are preferably cored out at 8 (Fig. 3) to lighten the casting and to save metal.

Within the above described recess in each casting 1 is an inner casting generally designated 9, which inner casting is formed with a horizontal flange 10 around its upper edge that rests directly on the horizontal shoulder in the outer casting 1 supporting the upper side of the inner casting flush with the upper edges of the side and end walls of the main outer casting. This flange 10 is provided with a plurality of ears 11 projecting outwardly therefrom, and the side walls of the recess in the casting 1 are recessed to receive these ears. The shoulder portion 7' of the outer casting is thickened below said ears as at 12 (Fig. 3) which thickened part is formed with a horizontally extending slot 13 opening at one end into the cavity in which the inner casting 9 is received. The upper side of each slot opens upwardly through the upwardly facing surface of the shoulder on which the flange 10 and ears 11 are supported. Each slot 13 is restricted in width along its upper edge, to pass the shank 14 of a bolt, and the enlarged lower portion of the slot slidably receives the polygonal-sided head 15 of such bolt. Thus the bolt is held against turning by the sides of the enlarged portion of the slot 13, as shown in Fig. 6.

The flange 10 at each of the ears 11 is vertically apertured to pass the shank 14 of each bolt when the inner casting 9 is dropped into place in the outer casting 1. The upper end 16 of each of said apertures is enlarged to receive nut 17 of bolt 14, and to enable a tap-wrench to be used for tightening the nut.

It is to be noted that when the inner casting 9 is in position in the recess in outer casting 1, the correspondingly tapered sides of the inner and outer castings are spaced apart, and also bottom 7 of the outer casting and bottom 18 of the inner casting are also spaced apart. The

outer edges of flange 10 and the edges of ears 11 adjacent the upper sides of the inner and outer castings are substantially together, but the outer edges of the flange and ears preferably taper slightly inwardly from their upper sides toward their lower sides, thus providing a space around flange and ears between the outer casting, and said flange and ears. The flange 10 is vertically cut away at its outer edge at spaced points, to provide openings 19 for molten babbitt or the like to be poured into the spaces between the inner and outer castings, and horizontal passageways 20 (Fig. 3) in the lower sides of flange at the lower ends of openings 19, communicate between the opposed slanted walls of the inner and outer castings and the space between the flange 10 and outer casting, to permit the molten metal to freely flow to between bottoms 7, 18, as well as filling the space between said opposed slanted walls.

After the babbitt 20 fills the spaces between the inner and outer castings, and nuts 17 are tightened on bolts 14 to securely clamp the flange 10 tight against shoulder 7', the molten babbitt 21 or the like is poured into the enlarged upper ends of the apertures in flange 10 to cover nuts 17. The upper edge of each of said apertures is cut away to receive a plate 22 which plate is welded at its edges to casting 9, thus completely sealing the nuts 17 against the elements and against being tampered with, until the plates 22 are removed and the babbitt 21 melted away.

This inner casting 9 is, in turn, formed with an upwardly opening recess substantially identical in structure with the recess receiving said inner casting 9. Within the recess in said inner casting is fitted the wearing block 23. A shoulder 24 supports the flange 25 of block 23 directly thereon, and the portion forming said shoulder is thickened below ears 26 on said block for forming slots 27 that receive heads 28 on shanks 29 of the block retaining bolts. The ears 26 fit in corresponding recesses in inner casting 9 and the flange 25 at each of the ears 26 is apertured to pass one of the shanks 29 of the block securing bolts. The upper end of each of such apertures is enlarged to receive nut 30 on each shank 29, which recess is filled with babbitt and then covered by a cover plate 31 that is welded in place in the same manner as described with respect to plates 22. The adjacent sides of the block 23 and the inner casting are correspondingly tapered below flange 25 and bottom 18 of the inner casting is spaced from bottoms 32 of the block 23 so that babbitt 33 may be poured into the space between the bottoms and sides of the block and corresponding walls of the inner casting 9. Pouring openings 34 are formed in the inner casting 9 around the substantially adjoining edges of the flange 25 and the inner casting and horizontal passages 35 communicate between the lower ends of said openings and the opposed tapered sides of the block 23 and said inner casting, all in the same manner as provided for with respect to the inner and outer castings 9, 1 respectively.

The upwardly facing sides of the outer casting 1, inner casting 9 and block 23 are cross grooved as at 36 for providing the grooves to receive the wheel flanges on car wheels passing over the castings and block 23. These grooves meet at their crossing point on the block 23, and in the case of crossing A (Fig. 1) one only of the frogs 37 (Fig. 2) is formed on the block 23, while on the remaining crossings B, C, D, both frogs 37

are formed on block 23. The reason for this is that at crossing point A, only the frog 37 receives any wear as the wear is taken at points 38 at opposite sides of the intersecting points of grooves 36, while in the crossing points B, C, both frogs 37 receive wear from the wheel treads. Crossing D may, of course, correspond to crossing A.

It is apparent from the above described construction, that by the use of an acetylene torch, the caps or cover plates 22, 31 may be readily removed and the babbitt around nuts 17, 30 removed to facilitate access to said nuts, thus enabling removal of the inner casting 9 or the block 23, without disturbing the pavement or main casting 1.

Also, when the crossing blocks, including the inner castings, are in place, the bolts and nuts that clamp the blocks and inner castings in place are fully concealed and cannot be tampered with readily, nor can moisture, etc., gain access thereto.

While the above specific description relates to a crossing of the type where the rails meet obliquely, the same construction is applicable to right angle crossings and to a switch frog and block mounting the same, as shown in my United States Letters Patent No. 2,231,232, dated February 11, 1941, each of which shows block supported by flange and shoulder construction as here disclosed.

It might be added, that the removal of the wearing block or inner casting is readily accomplished, in the event of a tendency of the same to stick in place, by the application of heat from a blow torch to the block or casting, adjacent its ends, until the babbitt melts, when application of water to the heated block or casting at the junctures of said block or casting, with each other or with the outer casting, will readily loosen the block or inner casting so it can be lifted out with the use of pry bars in openings 19 or 34.

It is highly important that the outer casting 1, in the form shown, extend beyond both of the frogs or along an appreciable length of switch frogs, and while the frogs on crossings of the type shown herein may be formed on the inner castings 9, it is preferable to form one or both frogs on a separate block, since these frogs are of special hardened steel that is relatively expensive.

The claims relating generally to track intersection structure without qualification, are intended to include intersections at switches or crossings, and are also intended to cover the construction for holding inner casting 9 in the main outer casting since it is obvious that the wearing block 23 is carried on the inner casting 9.

Having described my invention, I claim:

1. A track intersection structure comprising a main outer casting formed with an upwardly opening recess therein having lateral sides and a bottom; an inner casting fitted within said recess; means removably securing said inner casting in said recess; said inner casting being formed with an upwardly opening recess therein; a block removably fitted within said last mentioned recess; means removably securing said block in said last mentioned recess; the upwardly facing sides of said outer and inner castings and said block being substantially flush and respectively formed with aligned grooves providing continuing wheel tread supporting surfaces at one of the sides thereof respectively; said grooves intersecting at a point on said block whereby a frog is formed on said block; the means respectively securing

said inner casting in the recess in said outer casting and securing said block in the recess in said inner casting comprising bolts respectively carried by said inner casting and said outer casting, and slots formed in said inner casting and in said outer casting supporting the bolts carried by said inner casting and said outer casting vertically for lateral movement into the said recess in said inner casting and into the said recess in said outer casting respectively.

2. In a construction as defined in claim 1, the slots in said inner casting opening at one of their ends into the recess therein and closed by one of the side walls of said inner casting at their opposite ends, and the said block closing the open ends of said slots when fitted in the recess in said inner casting thereby closing the open ends of said slots to removal of the bolts into the recess in said inner casting.

3. A track intersection structure including: a main casting formed with a substantially rectangular, upwardly opening recess therein having lateral sides and a bottom; said sides being formed to provide an upwardly facing shoulder; a block removably fitted in said recess having a flange supported on said shoulder; upwardly opening horizontal slots formed in said shoulder, opening into said recess at one of their ends; the sides of each of said slots being restricted adjacent its upwardly directed slot opening; a vertical bolt slidably supported in said slot for movement horizontally in said slot and having a head engaging below the said restricted portion thereof; vertical openings formed in said flange passing said bolts; the upper end of each of said openings being enlarged and a nut on the upper end of each of said bolts in the enlarged upper end of said opening clamping said flange against said shoulder; closure plates secured to said block closing the upper end of said openings and extending over said bolts and said nuts, and the upwardly facing side of said block and casting being formed with a wheel flange receiving groove providing a wheel tread supporting surface at one side thereof.

4. In a construction as defined in claim 3, said block closing the ends of said slots that open into said recess and the opposite ends of said slots being closed by the side walls of said casting whereby said bolts are secured against removal from said slots until after said block is removed from said recess.

5. In a construction as defined in claim 3, the said enlarged upper end of each of said openings being filled with metal of a relatively low melting point surrounding said nuts; the upper edge of each of said openings being recessed, each of the said plates being fitted at its edges in said recess in a position with its upper surface substantially flush with the upper surface of said block and welded at its edges to said block.

6. A track intersection structure including: a main casting formed with a substantially rectangular, upwardly opening recess therein having lateral sides and a bottom; said sides being inwardly offset to provide an upwardly facing shoulder; a block removably fitted in said recess having a flange supported on said shoulder; an upwardly opening horizontal slot formed in said shoulder opening into said recess at one of its ends; the sides of said slot being restricted adjacent its upwardly directed slot opening; a vertical bolt slidably supported in said slot for movement horizontally of said slot and having a head engaging below the said restricted portion there-

of; a vertical opening formed in said flange passing said bolt; the upper end of said opening being enlarged and a nut on the upper end of said bolt in the enlarged upper end of said opening clamping said flange against said shoulder; said block closing the end of said slot that opens into said recess and the opposite end of said slot being closed by the side wall of said casting whereby said bolt is secured against removal from said slot only after said block is removed from said recess; and the upwardly facing side of said block and casting being formed with a wheel flange receiving groove providing a wheel tread supporting surface at one side thereof.

7. A track intersection structure including: a main casting formed with a central, upwardly opening recess therein; two opposite lateral sides of said recess being inwardly offset to provide upwardly facing shoulders at said sides; said

shoulders being formed with horizontal passageways each having the upper side thereof longitudinally slotted and each of said passageways and slots opening at one of their ends into said recess; a block removably fitted into said recess and having flanges; the body of said block being disposed across said open ends of said passageways and slots, and flanges integral with said block extending over said shoulders and over said slots; said flanges being formed with bolt openings disposed over said slots, and bolts extending through said openings and slots, said bolts having their heads disposed in said passageways and secured therein by the marginal portions of said slots and by the said body of said block, whereby upon removal of said block from said recess the said bolts may be slipped into said recess for replacement by new bolts.

VANGEL THEODOS.
